US00D500498S

(12) **United States Design Patent** (10) Patent No.: **US D500,498 S**
(45) Date of Patent: **** Jan. 4, 2005**

(54) **MOBILE COMMUNICATIONS DEVICE**

(75) Inventor: **Jun Katsumata**, Singapore (SG)

(73) Assignee: **Sony Ericsson Mobile**, Lund (SE)

(**) Term: **14 Years**

(21) Appl. No.: **29/170,075**

(22) Filed: **Oct. 31, 2002**

(51) LOC (7) Cl. **14-03**

(52) U.S. Cl. **D14/248**

(58) Field of Search **D14/253, 242, D14/250, 148, 240, 138, 144, 248; 379/419, 420.02, 420.04, 428.02, 428.04, 400, 457**
